UNITED STATES PATENT OFFICE.

JOSEPH C. CALHOUN, OF HOLLAND, MICHIGAN, ASSIGNOR OF ONE-HALF TO GEORGE P. HUMMER, OF HOLLAND, MICHIGAN.

PAD FOR PHOTOGRAPHIC-PRINTING MACHINES.

No. 888,585.

Specification of Letters Patent. Patented May 26, 1908.

Application filed February 11, 1907. Serial No. 356,761.

To all whom it may concern:

Be it known that I, JOSEPH C. CALHOUN, a citizen of the United States of America, residing at Holland, in the county of Ottawa and State of Michigan, have invented certain new and useful Improvements in Pads for Photographic-Printing Machines; and I do hereby declare the following to be a full, clear, and exact description of the invention, such as will enable others skilled in the art to which it appertains to make and use the same.

My invention relates to improvements in pads for photographic printing machines and more particularly to such machines as are shown in my co-pending application, Serial Number 317,275, filed May 17, 1906, for photographic printing machines, and its object is to provide an improved pad, having a smooth and yielding surface to engage the photographic paper and hold the same in contact with the negative, and to provide the same with various new and useful features hereinafter more fully described and particularly pointed out in the claims, reference being had to the accompanying drawings, in which:

Figure 1. is a perspective view of a device embodying my invention; Fig. 2. is a plan view of the same with the panel and flexible facing removed; Fig. 3. is a transverse section of the complete device taken on the line 3—3 of Fig. 2.; and, Fig. 4. an enlarged detail of one corner of the same.

Like numerals refer to like parts in all of the figures.

1 represents a frame of any preferred dimensions and provided with a back 2 secured therein, the frame and back constituting substantially a shallow tray, within which and secured to the back, are a series of coiled springs 3 to yieldingly support a movable panel 5 preferably a panel made of several plies of veneer, upon the surface of which panel is placed a thin layer of yielding material 6, preferably of a fabric known as "eider down". Over the outer surface of this material is placed a sheet of flexible material 7, preferably of rubber coated cloth, the edges of which extend beyond the panel on all sides and are secured to the edge of the frame 1 by means of any convenient fastenings 8, preferably tacks or small nails. This

sheet 7 serves to hold the elastic material 5 in place and provides a smooth surface to contact the paper. The margins of the sheet will yield as the panel is pressed inward and also serve to form a tight closure between the panel and frame. The springs 3 yieldingly support the panel to uniformly engage the paper over its entire surface and press the same closely down upon the negative. To guide this panel 6 when pressed within the tray, and to limit its outward movement as well, I provide a pair of interlocking hooks 4 near the respective corners of the tray, which hooks are respectively inserted in the back 2 and panel 5 and engage each other to limit the outward movement of the panel and when the panel moves inward, these hooks slide on each other and guide the panel, said hooks being arranged in pairs near the respective corners of the tray and with the hooks in the panel slidably engaging the sides of the respective hooks in the tray 75 toward the center of the tray whereby the panel is guided to move vertically.

What I claim is:

1. The combination of a tray consisting of a frame and a back secured therein, springs attached to the back, a panel yieldingly supported by the springs, and a sheet of yielding material extending over the surface of the panel and having flexible margins extending from the panel and secured to the frame of the tray.

2. The combination of a back, a marginal frame attached thereto, springs attached to the back, a panel yieldingly supported by the springs, elastic material supported by the panel, and a sheet of flexible material thereon, said sheet also having flexible margins extending from the panel and secured to the frame.

3. The combination of a tray consisting of a frame and a back secured therein, springs in the tray, a panel engaged and supported by the springs, and interlocking hooks slidably engaging each other and connecting the back and panel, said hooks being arranged in opposing pairs near the respective corners of the device and with the hooks in the panel slidably engaging the sides of the respective hooks in the tray toward the center of the tray.

4. The combination of a frame, a back in

the frame, springs attached to the back, a panel supported by the springs, hooks arranged in interlocking pairs and slidably engaging each other, said hooks also connecting the back and panel, and a layer of yielding material covering the panel, and a sheet of flexible material covering the yielding material and panel and extending beyond the

same and also attached at its margin to the frame.

In testimony whereof I affix my signature in presence of two witnesses.

JOSEPH C. CALHOUN.
